Primary Examiner — Mary Ann Calabrese*Assistant Examiner* — Hillary Catherine Shepard(74) *Attorney, Agent, or Firm* — REISING ETHINGTON, P.C.(57) **CLAIM**

The ornamental design for a foldable table frame, as shown and described.

DESCRIPTION

FIG. 1 is a perspective view of the foldable table frame; FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings illustrate portions of the foldable table frame that form no part of the claimed design.

1 Claim, 7 Drawing Sheets(56)
